US00D920933S

(12) **United States Design Patent** (10) **Patent No.:** **US D920,933 S**
(45) **Date of Patent:** ** *Jun. 1, 2021

(54) **SURFACE-MOUNT DEVICE**

(71) Applicant: **Putco, Inc.**, Des Moines, IA (US)

(72) Inventors: **James P. Elwell**, Grimes, IA (US);
James P. Elwell, II, Grimes, IA (US);
Joshua J. Burhite, Des Moines, IA
(US); **Tian Xiaojun**, Guangzhou (CN)

(73) Assignee: **Putco, Inc.**, Des Moines, IA (US)

(*) Notice: This patent is subject to a terminal disclaimer.

(**) Term: **15 Years**

(21) Appl. No.: **29/652,502**

(22) Filed: **Sep. 4, 2020**

Related U.S. Application Data

(60) Division of application No. 29/723,356, filed on Feb. 6, 2020, now Pat. No. Des. 899,384, which is a continuation-in-part of application No. 16/673,434, filed on Nov. 4, 2019, now Pat. No. 10,859,229.

(57) **CLAIM**

The ornamental design for a surface-mount device, as shown and described.

DESCRIPTION

FIG. 1 is a perspective view of a surface-mount device; FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

Structure and environment shown in broken lines form no part of the claimed design.

1 Claim, 4 Drawing Sheets
